18 Claims.

(Cl. 66—1)

This invention relates to the production of looped textile threads or yarns and constitutes an improvement of my copending application Ser. No. 95,333 filed Aug. 11, 1936, now Patent No. 2,143,230.

The present invention resides in a method according to which there is led to the looped thread to be produced one or more than one thread which may be looped with the looped thread or 5 may be run through it as a thread base.

There may also be led to the looped thread fibers or other loose material in such a manner that such material is securely bound into the looped thread.

Controlled thread brakes may be provided for effecting different tensioning relationships between threads guided to different needles in order that threads composed of loops of different sizes can be produced.

20 In order to attain an increase in working speed over that attainable by the constructions described in the prior specification, the needle which reciprocates lengthwise of its axis is provided with a vibrationless high-speed drive of 25 which the moving masses are reduced to a minimum. The drive acts directly on the needles.

Between the drive and the needles there is suitably interposed a vibration-absorbing resilient connection, which is connected on the one hand 30 to a balanced crank and on the other hand to a coupling-pin, which is connected to a needle support working in a bearing or the like. Vibrations manifest themselves at high speeds and would exercise adverse effects upon the insertions of the threads, so that irregular looping might result. The aforesaid resilient connection, 35 preferably a double link formed as a wire stirrup, absorbs the vibrations and prevents their transmission to the needle.

40 The insertion of the threads may be effected by movable thread guides, which are operated in such a manner by special mechanism for producing the needle motion that the inserted threads are engaged with continuous surety. As distinguished from the swinging or oscillating thread-guides described by way of example in the prior specification, the present invention provides for use of a thread guide which moves up and down and which inserts the threads in 45 the needle from above. It is also practicable, by means of a pendulous thread guide, to insert the threads sidewise in the needle. Further, with certain threads, it is also practicable to have stationarily fixed thread guides, the arrangement 50 being such that the threads coming from the

spools or the like are engaged with continuous surety by the receding needle hook.

The thread guides, where movable, are adjustable to suit the threads to be worked upon and they are of balanced construction and as light as possible, in order to minimise the mass of the moving parts. Thread-guide and needle are operated by the same driving parts so that accurate timing of the speed of both elements can be readily attained.

Between the thread-supply means on the one hand and the thread guide on the other hand thread brakes, or drag devices, can be interposed, and these may be composed mainly of spring-pressed brake discs between which the thread slips. By increasing or decreasing the spring stress and thus correspondingly the thread tension, the binding-in relationships can be regulated as desired. The spring pressure can be automatically subjected to periodic alteration by one or more than one thread-brake. For this purpose, there can be provided in connection with the spool or like thread-supply means a cam which, according to its shape, is subjected to periodic spring pressure in order to tension the 20 thread, and at other times leaves the thread free. The result of this is that the other threads which are being led to the same needle, and which are under no tension, become formed into irregularly spaced large or small loops.

30 By virtue of the binding-in devices thread structures can be produced which are practically unlimited as regards pattern. Thus, one can produce for example a single looped thread or a plurality of looped threads which are under the 35 same or different tensions. One or more additional threads can also be inserted in the looped thread, and these may constitute looped-in threads or they may constitute a thread base or core extending through the looped thread. Conveniently, the first sort of threads may be termed "binding" threads, whilst the second sort may be termed "foundation" threads. The individual threads of this thread structure may be led to the needle under uniform or variable tensions.

40 The advantage of the thread structure composed of binding and foundation threads resides not only in wide possibilities as regards patterning but also in the low ultimate strength. For example, in a looped thread composed of a single 45 binding thread and a single foundation thread, the basic thread strength is not sextupled ($2 \times 3 = 6$) by the looping operation, but merely quadrupled ($1 \times 3 + 1 = 4$). This means that as each 50 loop is formed by drawing a thread through a 55

noose located on the shank of a needle and comprising an advancing and a receding portion a completed loop on being cut through transversely to the direction of the thread will disclose three 5 thread ends. If a foundation thread is worked into a binding thread whose individual loops each comprise three thread portions, four thread ends will be produced on cutting the thread structure transversely to the direction of thread, and there 10 be six thread ends when two binding threads arranged side by side are cut. Accordingly, such a thread structure comes into consideration where a simple looped thread is too strong.

By adopting the improved method embodying 15 the present invention, with a binding thread and a foundation thread one can obtain, as in an ordinary method of looping, all strengths ranging from the finest genuine silk to the strongest textile thread, and moreover according to requirements and purposes the foundation thread 20 and the binding thread can be interchanged. Further, in carrying out the improved method, one can obtain narrow or wide loops as desired. Further, rubber threads, metal threads and other 25 threads difficult to work with can be bound-in without tension. Yarns difficult to spin or new sorts of yarns of little internal substance can be looped-in, for example with an artificial silk thread, without subjecting it to severe treatment.

30 Greatly increased tensile strength can be obtained according to the method adopted, and to a certain extent, working is made possible for the first time by the improved method.

Since the binding thread closely embraces the 35 foundation thread owing to looping, the binding thread draws itself into the foundation thread whenever the looped thread is pulled and high tensile strength is thus manifested. In use of artificial silk, genuine silk or wool-crepe-silk as the 40 foundation thread or as the binding thread, the improved method can be performed in a single cycle of operations to produce all the variations of bouclé, the effect of which can be further enhanced if different kinds (e. g. viscose or acetate) 45 or differently colored threads are used as foundation or binding threads. Further, threads or strands of different kinds and thicknesses can be embodied in the foundation and binding threads.

50 By introducing further binding-thread guides and further foundation-thread guides the thread structure can be varied as desired. The foundation-thread guides and one or more binding-thread guides work in timed correlation under 55 the control of a cam drum or of a patterning or chain device known per se. According to the setting of the pattern control means, the foundation threads for example can be forced to lie 60 crosswise in one or more of the loops of the binding thread, or in use of a single base or core the loops of both binding threads lie around a single foundation thread. Further, a plurality of binding-threads and a plurality of foundation 65 threads can be worked upon interchangeably as desired.

The present invention resides also in mechanism for performing the improved method. The mechanism has means for driving simultaneously 70 the needle and also a plurality of foundation-thread and binding-thread guides, which control the respective threads in the manner desired for the time being. The needle and thread guides necessary for the production of any required 75 thread structure are replaceably assembled in a

drumlike housing, noiseless and vibrationless working of the moving parts being obtainable.

The driving mechanism incorporates a rotary double-cam drum which are provided with cam parts for driving the guide rods for the needles. 5 The cam parts are so constructed that at each revolution of the drum the guide rods are twice moved to and fro, whereby noiselessness and freedom from vibration are attained. The body of the cam drum is constructed for reception of two 10 cam sets disposed one above the other, said sets being generally composed of interchangeable and transposable steel parts. The cam slopes are inclined at less than 30° in order to afford sure guiding and rolling action even at the highest 15 speed. Short and long followers, including rollers, are acted upon by the respective cams, the longer followers extending into register with both cams and the shorter followers extending into register with only the upper cams. The 20 longer followers will thus receive, in one revolution, double actuation in relation to the shorter followers. Thus, there is obtained the combination of one to two motions per revolution, the latter being required for two-thread patterning. 25 At the same time, it is immaterial whether at other parts of the drum's circumference still further motions for a single or double lift per revolution are added.

In so far as only a normal operation, that is a 30 single or plural operation, is to be undertaken, the lower cam parts are replaced by inactive parts of the same thickness. All the cam parts and their followers and the drum itself work in a closed housing which is filled with lubricant. 35 The cam parts can be pinned on the drum in a plurality of places from the exterior of the housing, for example at spacing of 180°, 90°, 45° or 30°, according to needs or requirements.

It is within the scope of the invention to let 40 the driven parts, according to the in-built curves, simultaneously carry out any desired motion as required in operation. Especially also is it possible by the mechanism to work more than once upon a thread, that is by using a plurality of 45 needles and thread guides to perform successively on the same thread their binding-in actions.

The invention also resides in mechanism for 50 performing the method by which fibrous or other loose textile materials can be added mechanically to the looped thread in such a manner that the additional material is incorporated in the thread by the looping action. At the same time, there is prevented disadvantageous dispersal or loss 55 of the material, which mostly is quite valuable. The insertion of the additional material can be effected by blast or by brushing, and by having the blast action or the brushing action variable, a wide range of patterning is available. By periodic displacement of the nozzle, through which 60 suitably the blast can be blown, further patterning effects are attainable. The additional material is securely bound into the body of the finished looped thread, and even quite light additions of material give a surface which is rough 65 and hairy and which is woolly to the touch. Further, the core can as desired be thin or thick in relation to the thickness of added material. The added material itself can be long or short and preferably would be mixed.

70 Embodiments of the invention will now be described by way of example with reference to the accompanying drawings, in which:

Fig. 1 shows in elevation mechanism for the 75 production of knitted or looped threads with

foundation threads, and Fig. 2 is a corresponding plan.

Figs. 3 to 5 show a needle guide and casting-off device in plan and in front and side elevation, respectively.

Figs. 6 and 7 show a looped thread diagrammatically to an enlarged scale.

Figs. 8 and 9 show diagrammatically, to an enlarged scale, thread formations each consisting of one binding thread and one foundation thread; and Figs. 10 to 17 show diagrammatically the manufacture of such thread in eight phases. Figs. 18 and 19 are perspective views of needle and thread guides in the phases according to Figs. 10 and 14, respectively.

Figs. 20 and 21 show diagrammatically to an enlarged scale thread formations each consisting of one binding thread and two foundation threads; and Figs. 22 to 29 show diagrammatically the manufacture of such thread in eight operations. Figs. 30 and 31 are perspective views of needle and thread guides in the phases according to Figs. 22 and 26, respectively.

Fig. 32 is a part view of means for regulating the tension of the thread.

Fig. 33 shows a looped thread of which the single looped-in thread has been bound in under different tensions.

Figs. 34 to 42 show mechanism including a rotary structure for the manufacture of looped threads with one or more foundation threads, and of these views:

Fig. 34 shows the mechanism in elevation and part longitudinal section. Fig. 35 is a part elevation of the thread guide. Fig. 36 shows the mechanism in front sectional elevation. Figs. 37 to 42 show developments and corresponding sections of guide cams arranged one upon the other on a drum constituting the rotary structure.

Fig. 43 is a diagrammatic view of a looped thread provided by a continuous blast operation with additional fibers. Fig. 44 is a diagrammatic view of a looped thread provided by an interrupted blast operation with additional fibers. Fig. 45 shows mechanism for automatically supplying the additional fibers and other textile materials and for inserting the same into the looped thread.

In the first embodiment of the mechanism, now to be described, the needle is driven by a crank and the operation of the thread guides is effected by cam discs or other suitable pattern apparatus.

Referring to Figs. 1 to 5, a bush 3 for the driving shaft 4 of the mechanism is located in a bearing 1 on the frame 2. At the free end of the driving shaft is located a crank 5 which may suitably be shaped as a disc, and on the crank pin 6 of the disc 5 a hardened connecting roller 7 is journaled. A vibration-absorbing resilient doubled wire stirrup 8 embraces at one end the connecting roller, the other end of the stirrup being pivotally connected to projections 9 on the needle support constituted by a rod 10. The needle rod, which is supported in a bearing 11 of the frame 2, has a needle clamp 12 with a clamping screw 13 for adjustably positioning the needle 14, which in this embodiment is of the latch type.

Beyond the roller 7, a crank roller 15 is journaled on the crank pin, and a crank-follower 17 forming part of a binding-thread guide 21 engages in the groove 16 of the roller 15. The crank-follower 17 consists in this embodiment of

a bent wire yoke, of which the otherwise free end is held rigid by a clamp 18. The wire yoke engages in a clamping nut 19 which is pivotally mounted on a bolt 20 fastened on the frame 2. At the front end of the clamping nut there is located the binding-thread guide 21, of which the forward end is bent substantially at right angles and terminates in a thread eye. In this example, the thread eye opens downwardly. To provide for adjustability to suit the nature and strength of the yarn in use at any given time, the yoke 17 is adjustably fastened in the clamping nut 19 by means of screws 23, and the binding-thread guide 21 is adjustably fastened by a screw 24.

The front part of the needle is guided in a slot 25 of the needle bed 27 which has a sloped surface 26, the needle bed being attached to the frame 2 by means of a holder 28. A casting-off member or stripper 29 is arranged at the front of the needle bed below the slot 25. The knitted thread formed by the needle is drawn between the said member and the needle bed over a drawing-off guide 30 by means of a resiliently driven winding-on apparatus 31. The winding-on apparatus, in this example, is formed as a drum or spool 32 located on a shaft 33 upon which is keyed a belt pulley 34. A belt 36 passes over the pulley 34 and over a pulley 35 which is directly or indirectly driven from the driving shaft 4. The shaft 33 which carries the winding drum 34 is braked in the present example by an adjustable weight 37 which may, however, be replaced by a spring. The tension in the driving belt and thus the driving effect can be altered in accordance with the properties of the thread being used by adjustment of the weight, or of the spring. Accordingly, a greater or smaller pull is exerted by the winding-on apparatus on the looped thread produced by the needle. Similarly, the pressure of the thread brake 38 located between the spool, cop or the like and the thread guide can be regulated.

The casting-off member 29 attached to the needle bed 27 runs substantially horizontally at its part 40, is bent downwards at its part 41 over the middle part of the needle and is directed upwardly at its part 42. The parts 41 and 42 constitute an angle containing the groove 43. The part 42 bears with its edge 44 against the needle bed 27 and the free end 45 of the casting-off member is bent away from the needle bed in order to simplify the introduction of the thread at the beginning of the operation. Above the winding-on apparatus 31 for the thread there is an automatic thread guide control. On the free end of a lever 47 which is pivotally mounted on the bolt 46 and which receives the necessary to-and-fro movements from a control projection 48, there is located an eye 49 through which the bound, looped thread coming from the drawing-off guide 30 is led. The control projection may be driven by any desired means (not shown) such as eccentrics or the like. The winding-on is carried out in the same way as in a spooling, spinning or twisting machine and may, as in these machines, be controlled by a laying-on apparatus for parallel winding or cross winding.

The crank disc is provided as a toothed wheel 50 which meshes with a complementary toothed wheel 51. The toothed wheel 51 is connected to a control drum 52, on the shaft 53 of which the pulley wheel 35 for the thread winding-on apparatus is mounted. The foundation-thread guides 55 and 56 are operated by a cam groove 54 in the drum 52. The guide 55, which is bent downward-

ly, is pivotally mounted on a bolt 57 and at its free end 58 it has a projection 59 which may suitably be provided with a roller and which engages underneath in the cam groove 54 as follows thereto. The guide 56, which is bent upwardly, is arranged above the guide 55 and is pivotally mounted on a bolt 60, and at its free end 61 it has a guide projection 62 which may suitably be provided with a cam-following roller.

10 Spools 63, 64 and 65 are provided from which the binding thread *a* and also the foundation threads *b* and *c* are led to the needle 14, which loops the threads alternately and the consequently produced looped thread *d* is led to the 15 winding-on apparatus 31.

In the second example, illustrated by Figs. 34 to 42, all the driving elements for the needle and thread guides are arranged as a rotary structure formed as a cam drum.

20 Referring now to Figs. 34 to 36, the driving shaft 71 of this construction of the mechanism is located in bearing bushes 72, 73 of a tightly closed housing 70, which would be filled with lubricant, for example grease. Outside one side of the 25 housing there are pulleys 74 for the drive and outside the other side there are pulleys 75 for the winding-on apparatus (not shown), all of these pulleys being keyed to the shaft 71. A hand wheel 76 is fixed to the free end of the 30 shaft. A drum 77 is mounted on the shaft and on its circumference are arranged, two cam assemblies 78, 79, one above the other. The cams consist of single cam pieces 78a, 78b, and 79a, 79b which are made of steel and are attached to the 35 drum body 77 by screws.

For different cam throws, different cams of corresponding slope are provided. For double movement, there are provided in place of pieces 80 underneath the cams 78, 79, further cams as 40 well as upper and lower straight pieces 81. For example, if the cam drum is used for driving a needle and a thread guide, then the arrangement in Figs. 37 and 38 is used, this arrangement being such that the cam pieces 78 are fixed on lower 45 members 80. If, on the other hand, different movements are to be obtained from the cam drum, and the latter is to serve, say, for driving thread guides of which one makes one movement during one rotation of the drum and the other 50 makes two movements during the rotation of the drum, then the cam arrangement according to Figs. 39 to 42 is used.

The short cam-following projection 82 which is moved by the upper cam pieces 79a, 78b is 55 moved to and fro once during one revolution of the rotary structure including the driving shaft 71, while the longer cam-following projection 83 which is controlled by the lower cam is moved to-and-fro twice during one revolution by means of the cam pieces 79a, 78a, 79b, 78b. The projections are either loosely attached to guide rods 84 for the needle 14 or are located on guide rods 85 which serve to operate the thread guide 86. The 60 latter are pivotally mounted on bolts 87 which are attached to a projection 88 on the forward end of which there is adjustably arranged, by means of screws 89, a needle bolster or guide 27. The free end of the thread guide has a longitudinal slit 90 in which a projection 91 on the 65 guide rod 85 engages.

It is practicable to use a stationarily fixed thread guide, such as indicated by dot-and-dash lines at 92, instead of the movable thread guide, 70 such a fixed guide being adjustably attached to

the housing 70 in suitable manner by means of screws 93 or the like.

Whether the thread guide be movable or fixed, the position of the thread eye 94 with reference to the needle hook must be such that the thread coming from the thread-delivery spool, cop, reel or the like is led at an inclination to the needle and is drawn off at a corresponding inclination at the other side of the needle as finished looped thread, so that the incoming thread always lies 10 across in front of the receding needle hook and can therefore be caught without fail by the hook and without any further assisting means.

From the large number of thread formations which can be formed by the above described 15 mechanisms there is shown by way of example in Figs. 8 to 19, a looped thread consisting of one binding thread and one foundation thread and in Figs. 20 to 31, a looped thread consisting of one binding thread and a plurality of foundation 20 threads (in the present case two).

Fig. 8 shows diagrammatically a binding thread *a* which is looped round a stronger foundation thread *b* which constitutes a base or core.

Fig. 9 shows a looped thread which consists of 25 a binding thread *a* and a foundation thread *b* of almost the same thickness.

Figs. 10 to 17 illustrate the production of a 30 looped thread according to Figs. 8 and 9 in eight phases and show diagrammatically in plan the needle 14 which moves to-and-fro axially in the needle guide.

Fig. 10: The needle 14 is going backwards. The binding thread *a* lies on the needle and is caught by the receding hook 14'. The foundation thread 35 *b* lies to the right of the needle.

Fig. 11: The binding thread is bound in by the retraction of the needle and the loop of the binding thread *a* already on the needle turns over the latch 14'' to the front. The foundation 40 thread *b* is at the right hand side of the needle.

Fig. 12: By further retraction of the needle the loop formed thereon is cast-off, the foundation thread being still at the right hand side of the needle. The displacement of the foundation 45 thread commences.

Fig. 13: The foundation-thread guide has positioned the foundation thread *b* on the left hand side of the needle. The thread *b* is under the needle and the needle advances.

Fig. 14: The needle advances further and the loop of the binding thread *a* has opened the latch 40 40'' of the needle so that the binding thread *a* can again enter the same. The foundation thread *b* is still to the left under the needle.

Fig. 15: The needle goes back. The loop of the binding thread *a* on the needle closes the latch 14''. A new loop is formed. The foundation thread *b* is still to the left under the needle.

Fig. 16: By further retraction of the needle 60 the loop is cast-off, the foundation thread *b* being still to the left of the needle. The displacement of the foundation thread commences.

Fig. 17: The foundation thread *b* is again to the right of the needle. The needle goes forward.

Fig. 18 shows in perspective the working position of the needle and threads according to Fig. 10. The needle 14 which moves to-and-fro in the slit of the needle guide 27 catches, by means 70 of its hook 14' on its backward movement, the binding thread *a* which comes from a spool and which is led through the eye 22 of the binding thread guide 21. The foundation thread *b* which comes from a spool or the like is, in this position, 75

led laterally to the right of the needle by the thread guide 55 and is entwined by the binding thread *a*. The looped textile thread produced in this way with a thread base is drawn off over a casting-off device 29 arranged on the needle guide 27 and over a drawing-off guide 30, suitably resiliently operating drawing-off apparatus, and wound up.

Fig. 19 shows the needle and needle guide in the working position according to Fig. 14. Here the foundation thread guide 55 is to the left of the needle and leads the foundation thread *b* under the needle along the casting-off device 29.

According to the second example, the looped thread consists of one binding thread and a plurality of foundation threads: and, more particularly, Fig. 20 shows two thick foundation threads *b* and *c* which are bound by a thin binding thread *a*.

Fig. 21 shows the same form of looped thread in which, however, the foundation and binding threads have approximately equal thicknesses.

Figs. 22 and 29 show eight phases of the production of a looped thread in accordance with Figs. 20 and 21, the needle 14 which moves axially to-and-fro in a needle guide being shown diagrammatically in plan.

Fig. 22: The needle 22 is being retracted. The binding thread rests on the needle and is caught by the receding hook 14'. The foundation thread *b* is to the right of the needle. The foundation thread *c* is to the left and under the needle.

Fig. 23: The binding thread is being bound in as the needle recedes; the loop of the binding thread which is already on the needle knocks forward the needle latch 14''. The foundation thread *b* is to the right of the needle. The foundation thread *c* is to the left and under the needle. Both foundation threads *b* and *c* during the operations are always between the loop on the needle and the newly laid-in binding thread *a*.

Fig. 24: By a further retraction of the needle the loop formed on the needle is cast-off; the foundation threads *b* and *c* are still in the original position. The displacement of the foundation threads commences.

Fig. 25: The needle is moving forward, the displacement of the foundation threads being completed. The foundation thread *b* is to the left and under the needle. The foundation thread *c* is to the right and over the needle.

Fig. 26: The needle is advancing further, the loop of the binding thread having opened the latch 14''' so that the binding thread can be again caught. The foundation threads *b* and *c* are still in their new positions.

Fig. 27: The needle is receding. The loop of the binding thread *a* on the needle closes the latch 14''' a new link of the thread chain is being formed. The foundation threads *b* and *c* are still in the same positions.

Fig. 28: By a further retraction of the needle the loop is cast-off. The foundation threads *b* and *c* change positions.

Fig. 29: The foundation threads have changed positions. The foundation thread *c* is to the left and under the needle. The needle is moving forward.

Fig. 30 shows in perspective the operative colocation of the needle and threads according to Fig. 22. The receding needle hook 14' catches on its retreat, the binding thread *a* which is guided by the binding-thread guide 22. The foundation

thread *b* supplied from a spool or the like is led to the right hand side of the needle by the needle by the thread guide 55. The foundation thread *c* supplied from a spool or the like is led to the right hand side and under the needle by the foundation-thread guide 56. Both foundation threads *b* and *c* are alternately or intermittently formed into loops by the binding thread *a*. The looped thread, consisting of two thread bases, which is formed in this way is drawn past a pressing-down guide 29 mounted on the needle guide 27 and is taken up over a leading-off guide 30 by means of a suitable resiliently acting take-up device.

Fig. 31 shows the needle and thread guides in the operative co-location according to Fig. 26. Here the foundation-thread guide 55 is to the left of the needle and guides the foundation thread *b* to the needle along the pressing-down guide 29. The foundation-thread guide 56 has its eye to the right hand side and above the needle and guides the foundation thread *c* to the right of the pressing-down guide at which both foundation threads *b* and *c* are formed into loops by the binding thread *a*.

In the manufacture of a simple looped thread such as is illustrated for example in Figs. 6 and 7, the threads supplied from the spools or such like supplying means pass through a thread brake 38. This consists, as Fig. 32 shows, of a bearing block 140 which is secured by means of screws 141 to a ledge 142 of the spool support 143 arranged above the loop producing mechanism. In the bore of this block a spindle 144 is journaled whose both ends are provided with screw-threads, 145 and 146. The spindle is held in the bearing block by means of nuts 147, 148. On the laterally projecting part of the spindle 144 is disposed a helical spring 149 which acts upon two brake discs 150, 151. Between the brake disc 151 and the nut 148 there is arranged desirably a bush or a spacing ring 152. The spring pressure can be altered by two nuts 153 and 154 on the threaded part 145 of the spindle, the nuts being desirably provided with milled edges.

Above the spool support, on whose spindles 155 spools 156 (or cops, or the like) are mounted, there is an apparatus 157 whose action is to regulate automatically the tension of the thread. This consists of a bearing 158 which is secured to a frame 159 located above the spool support. A shaft 160 is journaled so as to be freely turnable in the bearing 158 and a spool 162 is loosely secured to the shaft by means of cones 161. By means of their bores these cones are longitudinally displaceably arranged on the shaft 160 and somewhat slotted at their front end which thus spreads elastically apart. By displacing the two cones relative to one another on the shaft 160 and introducing them into the longitudinal bore of the spool 162 they are secured to the shaft 160 in a simple manner and can be instantly detached again. The shaft carries moreover a cam disc 163 which is connected fast to the shaft by means of a screw 164. Owing to its shape, the cam disc tends to rotate like the spool 162 connected with it in such manner that the mass of the disc 163 is located below, as indicated in Fig. 32. A spring 165 on the bearing 158 is adapted to bear laterally against the cam disc. The spool 162 on the shaft 160, actuated by the thread *g* as it is consumed on its being worked upon by the needle 14, is intermittently braked by the spring 165 during each revolution. However, as soon as the effective part of the cam disc 163

moves out of engagement with the spring, the cam disc turns suddenly downwards due to its weight and so frees the thread *g*. The thread *g* is conducted to the thread brake through the 5 thread guide 167 on the arm 166 of the bearing block 140 and from there is led to the thread guide 92. The threads *e* and *f* supplied from spools 156 (or other supply means) are conveyed to the thread-guide 92 through thread-eyes 168 10 and a thread guide 170 provided on an arm 169 of the bearing block.

Fig. 33 shows a looped thread composed of three threads and produced by means of the apparatus shown in Fig. 32, in which merely the 15 thread *g* is tensioned, and irregularly tensioned, while the threads *e* and *f* are led to the needle under the tension effected by the springy thread guide 170. In consequence of the variable tension of the thread *g* caused by the cam disc 163 20 the thread *g* is temporarily tightened and takes the threads *e* and *f* along which thus form wider irregular loops.

Mechanism for producing looped threads with bound-in added fiber or such like material is illustrated by Fig. 45. As shown, the mechanism includes a support 2 on a frame 100 for the needle-operating means, the crank 5 of which, suitably a disc, carries a crank-pin 6 to which is connected a wire stirrup 8 which absorbs any vibration in the needle drive. The forward end of the wire stirrup engages a coupling pin 9 of the needle rod 10 to whose front end the latch needle 14 is releasably secured, said rod being axially movable in the bearing 11 of the support 2. At 35 the forward side of the support 2 is fixed a needle guide 27 to which is applied a resilient pressing-down guide 29. Underneath this guide 29 is a located a leading-off guide 30 which guides the looped thread through the guide eye 49 to a resiliently acting thread take-up device.

The thread take-up consists in this example of a spool 32 on the rotatable shaft 33, a pulley 34 on which is connected by means of a belt 36 with a pulley 102 mounted on the driving shaft 101. The crank 5 on the shaft 1 has a pulley 103 which is connected by a belt 104 with a pulley 105 on the crank shaft 1.

The frame 100 has a bracket 107 on whose arm 108 a fiber containing hopper 109 is releasably secured. In the container 109 a pressure cover 110 is arranged which by the action of its weight feeds the fibers to a conveyer 111. This conveyer consists of two conveyer brushes 113 co-operating with strippers 112, composed of counter brushes 55 or strips. The parts 112, 113 are arranged in a housing and receive their drive through a belt 114, pulleys 115 and a belt 116 from a pulley 117 on the crank shaft 1.

The conveyer 111 delivers to a receiving funnel 60 119 which is turnable about an axis 118 and whose inclination can be adjusted through a rod 120 and a rod 121 by an adjusting lever 123 turnable about a pivot 122. The lever 123 can be fixed by stops 124 in the position which it for the 65 time being occupies. The forward end 125 of the funnel 119 is disposed at a suitable inclination and it delivers into a guiding funnel 126 which is turnable about a pivot 128 on a lug 127 fixed to the bracket 107 of the frame and is fixed but 70 adjustably supported in the elongated slot 129. The mouth 130 of the guiding funnel 126 is arranged above the needle 14 in such a way that the fibers in the trough are guided with certainty to the needle and can be securely bound-in by 75 means of the binding thread *a*. The thread *a*

is in this example unwound from a reel 131, which is turnable about a pivot 132 on an arm of the bracket 107, but instead of the reel any other suitable supply means can be used, for example cops or bobbins.

The thread *a* supplied from the reel 131 is led past a stationarily fixed thread guide 22 to the needle 14 where the fibrous material issuing from the guiding trough 126 is bound-in with the thread *a*. Fibers which drop past are collected 10 by a receiver 133 arranged under the needle and can, in consequence, be used again. Conveniently, the receiver can be provided with a waste pipe, suction pipe, or the like (not shown) by means of which the unused fibrous material is conveyed to 15 a collecting container from which it can later be resupplied to the container 109.

At a convenient part of the frame 100, in this example on the arm 108, a compressor 134 is arranged which supplies compressed air through a 20 conduit 135 to a nozzle 137 turnable about an axis 136. The conduit 135 includes a valve 138 (or a throttle or other regulator) which can be operated by hand through the intermediary of a lever 139. The lever 139 could however be automatically operated by means of suitable controlling mechanism (such as an eccentric or cam, not shown) connected by means of suitable rods (not shown) so that an alternate opening and closing of the valve in a regular or irregular manner may 30 be obtained as desired.

Intermittent interruption could additionally or alternatively be attained by intermittent operation of the brushes 112, 113 or by varying the 35 disposition of the funnel 119.

Fig. 43 shows a looped thread manufactured by this mechanism in which the fibers have been delivered uniformly.

Fig. 44 shows a looped thread which has resulted from an intermittent interruption of the 40 fiber supply.

I claim:

1. A method of producing looped textile thread consisting in leading-in a binding thread from a source of supply, guiding said thread for the performance thereon of a looping action, leading-in also a foundation thread, forming the binding thread into a chain of loops, guiding said foundation thread, to-and-fro sidewise into engagement with the binding thread, said binding thread being looped so that the foundation thread extends through the loops, withdrawing the finished looped thread which incorporates said binding and foundation threads and winding-up said looped thread.

2. A method according to claim 1, in which a plurality of foundation threads are led-in and are guided to-and-fro sidewise so that one foundation thread alternates in relation to another.

3. A method of producing looped textile thread 60 consisting in leading-in a binding thread under tension from a source of supply, guiding said thread for the performance thereon of a looping action, leading-in also under tension a foundation thread, forming the binding thread into a 65 chain of loops, imparting periodic variation to the tension under which the binding thread is led, guiding said foundation thread to-and-fro sidewise into engagement with the binding thread being looped so that the foundation thread extends through the loops, withdrawing the finished looped thread which incorporates said binding and foundation threads and winding-up said looped thread.

4. Mechanism for producing looped textile 75

thread comprising a loop-forming needle, means for reciprocating said needle, means for guiding binding thread from a source of supply to said needle for formation thereby into a single looped thread, at least one guide for leading a foundation thread to the binding thread where acted upon by said needle, means for actuating said guide to-and-fro sidewise to cause the foundation thread to extend through loops formed in the binding thread, a patterning device for controlling the actuation of said guide, and means for withdrawing the finished looped thread and winding it up.

5. Mechanism for producing looped textile thread comprising a loop-forming needle, movable guide means for leading thread from a source of supply to said needle for formation thereby into a single looped thread, a rotatably mounted cam-bearing structure, means for rotating said structure, followers engaging the cams borne by said structure, said followers being connected to said needle and guide means individually, said cams acting through the respective followers to reciprocate said needle and to move said guide means up and down in order to bring the thread into looping relationship with the needle, and means for withdrawing the finished looped thread and winding it up.

6. Mechanism according to claim 4, comprising also means for moving the binding-thread guiding means up and down in relation to the needle's path of reciprocatory motion, the timing of the movement of said guiding means being such that the binding-thread is made to engage

35 said needle from above.

7. Mechanism according to claim 4, in which the needle has a hook and the means for guiding binding thread consists of a stationarily fixed guide arranged to lead said thread at an inclination across the path of said hook for engagement thereby.

8. Mechanism according to claim 4, in which the binding-thread guiding means consists of a pivotally mounted guide, said mechanism comprising also a crank, means for rotating said crank, and a crank-follower consisting of a yoke slidably engaging said crank, said follower being connected to said guide to oscillate it as the crank rotates.

50 9. Mechanism according to claim 4, in which there are a plurality of foundation-thread guides each pivotally mounted and each provided with a thread-guiding eyelet, and in which said guides are pivoted to-and-fro by their actuating means to displace the respective eyelets from left to right and from right to left above the path of the needle's reciprocatory motion.

10. Mechanism according to claim 4, in which there are a plurality of foundation-thread guides 55 respectively made as levers, cam-followers on

said levers, thread-guiding eyelets on said levers, a control drum provided with cams engaged by said cam-followers, and means for rotating said drum to constrain the levers to move to-and-fro and displace their eyelets from left to right 5 and from right to left above the path of the needle's reciprocatory motion.

11. Mechanism according to claim 4, in which the means for reciprocating the needle comprise a rotary driver, a reciprocably mounted needle 10 support, and a vibration-absorbing resilient member connecting said driver and said support.

12. Mechanism according to claim 4, in which the means for reciprocating the needle comprise a balanced crank, means for rotating said crank, 15 a reciprocably mounted needle support, a coupling pin on said support, and a vibration-absorbing wire stirrup pivotally connected to said crank and to said pin.

13. Mechanism according to claim 4, in which 20 the means for reciprocating the needle comprise a rotary driver, said driver including a crank roller, a reciprocable needle support, projections extending oppositely from said support and a double lever pivotally attached at one end to 25 said roller and at the other end to said projections.

14. Mechanism according to claim 4, in which the means for reciprocating the needle include a rotary driver and the patterning device is a rotatable control drum, and in which intermeshing gear-wheels are provided on said driver and on said drum respectively.

15. Mechanism according to claim 5, in which the rotatably mounted cam-bearing structure 35 is provided with two sets of cam parts, these sets being arrangeable in superimposed relationship, and in which the cam-followers on the needle and guide means are made of different lengths corresponding to the height on said 40 structure of the cam parts that the respective followers engage.

16. Mechanism according to claim 5, comprising also a lubricant container made as a closed housing, the cam-bearing structure and the cam-followers being supported to work in said housing.

45 17. Mechanism according to claim 5, in which the means for driving the cam-bearing structure includes a rotary driving shaft to which said 50 structure is secured, said mechanism comprising also drive-receiving gear coupled to said shaft and drive-transmitting gear coupling said shaft to the means for withdrawing and winding-up the looped thread.

18. Mechanism according to claim 4, in which a binding thread and a plurality of foundation threads are controlled by a pattern mechanism.
